PORTABLE WASTE RECEPTACLE

Thomas E. Brown and Thomas H. White, Statesville, and
Richard M. Brotherton, Mooresville, N.C., assignors to
Rubbermaid Industrial Products Corporation, States-
ville, N.C.

Filed Feb. 16, 1973, Ser. No. 332,996

Term of patent 14 years

Int. Cl. D12—02

U.S. Cl. D7—189

FIG. 1

FIG. 2

FIG. 3

FIG. 4

FIG. 1 is a front perspective view of a portable waste receptacle embodying our new design.

FIG. 2 is a top plan view thereof.

FIG. 3 is a sectional view taken on line 3—3 of FIG. 2.

FIG. 4 is a rear elevation thereof.

The unseen side is a mirror image of the side shown.

We claim:

The ornamental design for a portable waste receptacle, as shown and described.
